PERRY CASSIDY, OF DARIEN, CONNECTICUT, ASSIGNOR TO THE BABCOCK & WILCOX COMPANY, OF BAYONNE, NEW JERSEY, A CORPORATION OF NEW JERSEY

HEAT-INSULATING CASING

Application filed September 9, 1926. Serial No. 134,355.

My present invention relates to casings, such as are commonly used for enclosing furnaces, boilers and the like to prevent the passage of heat from such structures, and will be best understood from the following description and the annexed drawings, in which Fig. 1 is a section of a portion of a boiler furnace wall and a boiler with a casing embodying one form of my invention; Fig. 2 is an enlarged view of a portion of Fig. 1 on the line 2-2 of Fig. 3; Fig. 3 is a view of Fig. 2 looking in the direction of the arrows 3-3 of Fig. 2, and Fig. 4 is a view similar to Fig. 2 but showing a modification.

Like reference characters indicate like parts in the various views.

In heat-insulating casings, there is commonly provided a layer of any heat-insulating material which is ordinarily covered on the exterior and sometimes on the interior by a sheet metal covering. These coverings are made up of metallic plates and the casing is further provided with stiffening members extending along the sheet metal covering to hold the parts in position, the ends of these stiffening members being ordinarily connected to the framing of the furnace or other structure to which the casing is applied. As heretofore constructed, the casing covering and the stiffening members have been arranged so that there are large metallic paths for heat flow through the layer of the heat-insulating material, thus nullifying to a large degree the effectiveness of the heat insulation. By my present invention, I provide a means for holding the parts of the casing in position and, at the same time, minimize or entirely avoid any such metallic paths through the heat-insulating layer. Furthermore, the panel plates which cover the heat-insulating material are flat and without flanges and may be sheared into plates of the desired size from sheet metal stock.

In the illustrative embodiment of my invention shown in Figs. 1, 2 and 3, the refractory wall 10 is provided exteriorly with a layer of heat-insulating material 11 and a sheet metal exterior covering made up of plates 12. Extending along the exterior of the casing are stiffening members 13, the ends

of which may be connected to the framing of the boiler setting. In the illustrative arrangement, the stiffening member is T-shaped in section, with an enlarged head 14 connected to the body portion of the stiffening member. The adjacent edges of a pair of plates 12 are separated by the body portion of the stiffening member 13 with the head 14 inside of the plates 12, this body portion extending only a small distance inside the plates 12 and being buried in the heat-insulating layer 11, as shown best in Fig. 2. A packing 15, preferably in the form of a pliable strip of material not affected by heat extends along the joint between the edges of the plates 12 and the stiffening member 13, as shown in Fig. 2, and a metallic bar 16 is laid against this packing strip.

Spaced along the body portion of the stiffening member 13 are pressure devices by which the bars 16 are pressed toward the plates 12 and toward the stiffening member 13 in such a way that the plates 12 are clamped against the head 14 and so that the packing 15 is also pressed into the joint between the stiffening member and the edges of the plates. In the form illustrated, each pressure device has a double-ended bolt 17 passing loosely through an opening 18 in the body portion of the stiffening member, each end of this bolt passing loosely through a bar 19 with the outer end of the bar resting against the body portion of the stiffening member 13 and its inner end resting against one of the bars 16, the ends of the bolt 17 being bent so that these ends are at right-angles to the surface of the bar 19. On tightening up the nuts 20 on the bolt 17, it will be obvious that each bar 19 is forced both vertically and horizontally in Fig. 2, and since the reaction of the bolt is against the body portion of the stiffening member 13, the net result is that the plates 12, the head 14 and the packing strips 15 are all clamped together and held in position so that the plates 12 are fastened to the stiffening member 13 and, at the same time, the joint between the edges of such plates and the stiffening member are tightly sealed.

The arrangement shown in Fig. 4 is for

what is known as a double casing used in some places where the heat-insulating material is not held against a refractory wall, as is the case in Fig. 2. In such casing, both the exterior and the interior of the refractory layer 21 is provided with a metallic covering made up of plates 22 on the exterior of the layer and plates 23 on the interior of the layer. The stiffening member 13 and the arrangement by which the edges of the plates 22 are held against the stiffening member and the joint sealed are the same as those illustrated in Fig. 2 and need not be described again.

15 Preferably the edges of the plates 23 on the interior of the casing are spaced apart a distance somewhat greater than the width of the head 14 of the stiffening member and the layer of heat-insulating material opposite this space may be continued as by a block 24 of some suitable heat-insulating material or may be filled with a mass of plastic insulation. The space between the edges of the plates 23, 23 may be covered by an auxiliary covering plate 25 which may be fastened to one of the plates 23. Where the casing is accessible from its interior side, it is obvious that the entire casing may be assembled before the block 24 is placed in position and covered by the auxiliary plate 25.

30 Preferably the plates 22 and 23, with the insulation 21 between them, are formed into panels, held together by bolts 26 in the usual manner, with a washer or packing 28 between the metallic washer 27 and the adjacent plate. The panels are readily moved into place from the exterior because of the cutting-away of the plates 23 to form an opening wider than the head 14 of the fixed stiffening member 13.

40 It will be noted that the pressure devices are located entirely outside the plates, so that the casing can be placed in position and the pressure devices then applied, without requiring access to the inside of the plates.

45 It will be understood that the arrangements which I have described are merely illustrative and that the embodiment of my invention may be widely varied. It will also be understood that certain features of my invention may be used independently of other features.

I claim:

50 1. A casing comprising a plurality of separate flat metallic plates, members extending along said plates, each of said members having a portion extending between the adjacent edges of a pair of plates and an enlarged head on one side of said plates, a packing at the joint between said edges and said member, means to hold the edges of said plates against said head and the packing against said plates and the body portions of said members, said means comprising a metallic bar extending along said packing parallel to the joint, and means, connected to said mem-

ber, to press said metallic bar toward said plates and toward said body portion.

2. A casing comprising a plurality of separate flat metallic plates, members extending along said plates, each of said members having a portion extending between the adjacent edges of a pair of plates and an enlarged head on one side of said plates, a packing at the joint between said edges and said member, means to hold the edges of said plates against said head and the packing against said plates and the body portions of said members, said means comprising a first metallic bar extending along said packing parallel to the joint, a second bar having one end resting against said body portion and the other end resting on said first bar, and a pressure device connected to said member to force said second bar and said first bar toward said plates and toward said body portion.

3. A furnace casing comprising a plurality of separate flat metallic plates, members extending along said plates, each of said members having a portion extending between the adjacent edges of a pair of plates and an enlarged head on one side of said plates, bars extending along the opposite sides of said plates, packing material interposed between said bars and said members and between said bars and said plates, and clamping means for forcing said bars towards said plates and said members and said heads against said plates whereby substantially airtight joints are formed.

4. A furnace casing comprising a plurality of separate flat metallic plates, members extending along said plates, each of said members having a portion extending between the adjacent edges of a pair of plates and an enlarged head on one side of said plates, a packing at the joint between said edges and said member, and means to hold the edges of said plates against said head and the packing in the joint between said member and said plates whereby said casing is rendered air tight.

5. A furnace casing comprising a plurality of separate metallic plates, members extending along said plates, each of said members having a portion extending between the adjacent edges of a pair of plates and an enlarged head on one side of said plates, bars extending substantially parallel to said plates and on opposite sides of the joint between the edges thereof, packing means interposed between said bars and said plates, and clamping means acting between said members and the respective bars and constructed and arranged to create pressure between each of said bars and the associated member and plate.

6. A furnace casing comprising a plurality of separate metallic plates, members extending along said plates, each of said members having a portion extending between the adjacent edges of a pair of plates and an en-

larged head on one side of said plates, bars extending substantially parallel to said plates and on opposite sides of the joint between the edges thereof, a packing strip located at the joint between a plate and the associated member, and means comprising said bars for exerting pressure against said strip in the direction of the head and of the extending portion of the member, whereby
10 the joint between said plate and said associated member is sealed.

7. A furnace casing comprising a plurality of separate metallic plates, members extending along said plates, each of said members having a portion extending between the adjacent edges of a pair of plates and an enlarged head on one side of said plates, bars extending substantially parallel to said plates and on opposite sides of the joint between the
15 edges thereof, a heat insulating pad of yielding material interposed between each of said bars and the associated plate and member, and clamping means constructed and arranged to force each of said bars against said
20 pad in the directions of the associated plate and member and said head against the opposite sides of said plates.
